UNITED STATES PATENT OFFICE.

LEWIS A. TYSON, OF HANKINSON, NORTH DAKOTA.

DESIGN FOR A HOE-BLADE.

48,090.

Specification for Design.

Patented Nov. 2, 1915.

Application filed May 29, 1915. Serial No. 31,300. Term of patent 14 years.

To all whom it may concern:

Be it known that I, LEWIS A. TYSON, a citizen of the United States, residing at Hankinson, in the county of Richland and State of North Dakota, have invented a new, original, and ornamental Design for Hoe-Blades, of which the following is a specification, reference being had to the accompanying drawing, forming part thereof.

Figure 1 is a plan view of the hoe blade,

showing my new design, and Fig. 2 is an edge view of the hoe blade, showing my new design.

I claim:

The ornamental design for a hoe blade, as shown.

LEWIS A. TYSON.
